UNITED STATES PATENT OFFICE.

JESSE JEFFERS, OF UXBRIDGE, MASSACHUSETTS, ASSIGNOR TO WHITIN MACHINE WORKS, OF WHITINSVILLE, MASSACHUSETTS, A CORPORATION OF MASSACHUSETTS.

BUILDER-MOTION.

1,373,508.

Specification of Letters Patent.

Patented Apr. 5, 1921.

Application filed November 11, 1918. Serial No. 262,100.

To all whom it may concern:

Be it known that I, JESSE JEFFERS, a citizen of the United States, and a resident of Uxbridge, in the county of Worcester and 5 Commonwealth of Massachusetts, have invented certain new and useful Improvements in Builder-Motions, of which the following is a specification.

My invention relate to builder motions 10 for spinning and winding machines.

The object of the invention is to provide simple and effective means for positioning the yarn traverse rod prior to the commencement of the operation of winding the 15 yarn upon the bobbins. In winding machines, as usually constructed, the yarn builder mechanism is located in the lower part of the machine in close proximity to the floor. The proper starting position of 20 the yarn traverse rod is obtained by the operative by means of a bell crank wrench transmitting a rotary motion to the builder shaft. The act of performing this operation is somewhat tedious to the operative owing 25 to the stooping position that has to be taken to accomplish the purpose. By means of my invention this operation is accomplished by the operative while in a standing position and he is thus free to exert the necessary 30 force without the tiresome effects.

With the above mentioned object in view, the invention consists in the novel construction and combination of parts hereinafter described, illustrated in the accompanying 35 drawings and pointed out in the claim here-to appended; it being understood that various changes in form, proportion, size and minor details of construction within the scope of the claim may be resorted to without 40 departing from the spirit or sacrificing any of the advantages of the invention.

To more fully comprehend the invention, reference should be had to the accompanying drawings, wherein—

45 Figure 1 is a fragmentary end view showing my invention applied to a quill winding machine.

Fig. 2 is a side view of the same.

Fig. 3 is a fragmentary side view of my 50 improved builder motion lever.

Fig. 4 is a top plan sectional view of builder motion on line A B of Fig. 2 showing the manner of hanging the builder motion lever to the frame of the machine.

Fig. 5 is an end view of the builder motion "take-up" device. 55

Fig. 6 is an end view of the locking device for the "winding-down" shaft.

Fig. 7 is a top plan view of Fig. 6.

Referring more particularly to the several 60 views of the drawings, wherein like characters of reference designate corresponding parts, 1 indicates the end leg of a winding machine, 2 the connecting bar between the legs (but one of the legs being shown), 3 65 the bolster rail for holding a plurality of spindle bolsters 4, 5 the bobbins on the spindles 6, 7 the traverse rod to which a yarn guide wire 8 is fastened for each bobbin. The traverse rod rises and falls a pre-determined amount depending on the length and kind of bobbin desired to be filled. Motion is communicated to the traverse rod 70 through the push rod 9 actuated by the bell crank lever 10 the upper arm of which is connected by a chain 11 to the builder motion lever 12 fulcrumed on a stud fastened to the end leg 1. A vibratory motion is imparted to the lever 12 by the cam 14 acting on the follower roll 15 fastened to the 75 lever 12.

The chain 11 is fastened to the periphery of the flanged pulley 16 and is wound thereon by a rotary motion imparted to the pulley by means of the worm gear 17 actuated by 80 the worm 18 on the builder shaft 19. On the outer end of the shaft 19 is fixed a ratchet gear 20. A pawl 21, Fig. 5, acting with the teeth of the ratchet gear, is pivoted to the carrying lever 22 which is in a swing- 85 ing relation with the hub of the ratchet gear. On the outer end of the pawl carrying lever 22 is a lug 23 provided with a hole in a sliding relation with the take-up rod 24 fixed to a stationary part of the machine. The 90 movement of the pawl with relation to the ratchet gear is controlled by two abutting collars 25, adjustably mounted on the take-up rod 24, one above the lug 23 and the other below. The pawl is maintained in contact 100 with the teeth of the ratchet gear by the compression of the spring 26 acting between the carrier arm 22 and the tail 27 of the pawl. As the builder motion lever 12 has a positive vibratory motion imparted to it by 105 the cam 14, it is evident that at each upward movement the lug 23 will be carried against the upper abutment collar 25 thus causing

the pawl, as the motion continues upward, to so act against the ratchet gear as to revolve it and through its connections with the flanked pulley 16 a predetermined 5 amount in the length of the chain 11 is unwound and thereby the position of the traverse rod is varied.

When the bobbins have attained their full 10 traverse they are removed from the machine and before a new set can be started it is necessary for the operative to wind down the traverse rod which he does by means of a bell crank wrench acting on the end of the builder shaft. The position that he has to 15 take in doing this is very awkward and uncomfortable and where it has to be done many times during the day's routine, becomes very tiresome to him.

The foregoing construction and description 20 is characteristic of builder motions of winding machines as made at the present time.

In my improved construction the builder 25 lever 12, Fig. 4, is provided with an enlarged hub 28 loosely mounted on the hollow stud 29 which is securely fastened to the frame 1 by the collar 30 and nut 31. The hollow stud forms a bearing for a short auxiliary shaft 32 on the outer end of which is 30 fixed the bevel gear 33 and on the inner end a skew gear 34 is fastened. This gear meshes with gear 35 fixed to the builder shaft 19. The bevel gear 33 meshes with bevel gear 36 fixed to the "wind-down" shaft 37 held in 35 bearings 38 and 39 fixed to the frame of the machine. At the upper end of the shaft 37 a handle is fixed by means of which the operative can impart a rotary motion to the flanged wheel 16 through the shaft 37, bevel 40 gears 36 and 33, shaft 32, skew gears 34 and 35, builder shaft 19, worm 18 and worm gear 17.

In "winding-down" the traverse it is necessary to reverse the direction of rotation of 45 the ratchet gear, this cannot be done while the pawl is in contact with the teeth of the ratchet gear; in my improved construction means are provided for disconnecting the pawl from the ratchet gear whenever it is 50 desirable. The preferred means shown in the drawings consists of a foot lever 40 pivoted to the frame 1 at 41, a chain or cord 42 drawn over guide rolls 43 and 44 connecting with a lug on the pawl 21. By this construction a depression of the foot lever by 55 the operative results in disconnecting the pawl and ratchet gear.

During the winding operation of a set of

bobbins an intermittent motion exists in the members of my improved construction due 60 to the action of the pawl on the ratchet gear. In order to eliminate part of this motion I provide a "cut-out" device for the "wind-down" shaft. Referring to Figs. 6 and 7 the "wind-down" shaft 37 is slidably 65 mounted in its bearings so that by pushing the shaft down sufficiently to disconnect the teeth of gear 36 from that of gear 33, rotation of the shaft 37 is stopped. A stop collar 45 fastened to the shaft 37 and abutting 70 against the bearing 39 limits the extent of the movement of the shaft to disconnect the gears.

When it is desired to make use of the "wind-down" motion the operative pulls 75 up the shaft 37 so that the gears 36 and 33 are in mesh and then locks the shaft in this position by the locking arm 46 pivoted to the foot of the bearing 39. This arm abuts against an adjustable collar 47 fastened to 80 the shaft and thus the shaft and its gear are securely held in operating position. Then the operative by a slight movement of his foot disconnects the pawl and the ratchet gear and at the same time winds down the 85 traverse rod by rotating the handle of the "wind-down" shaft. The necessary movements to perform this operation by the operative is done in a standing position without any discomfort whatever thus being conducive to the contentment and good health 90 of the operative.

I claim:

In apparatus of the class described containing the following instrumentalities, viz: 95 a plurality of spindles, a traverse member, yarn guiding means installed thereon, a cam controlling the movements of the traverse member, a builder lever actuated by the cam, bearings on the lever, a take-up 100 shaft supported in the bearings, means for imparting an intermittent rotary motion to said shaft, a chambered stud serving as a fulerum to the builder lever, an auxiliary shaft rotatable in bearings formed in the 105 chambered stud, connecting gearing between the auxiliary shaft and take-up shaft, a manually operated "wind-down" shaft 110 transmitting motion to the auxiliary shaft, means to maintain the "wind-down" shaft in or out of connection with the auxiliary shaft and locking means for the same.

In testimony whereof, I have signed this specification.

JESSE JEFFERS.
